USPC D28/4, 9, 10, 36, 92, 93, 99; 132/212, 132/216, 286, 333

The ornamental design for an artificial lash extension, as shown and described.

CPC ... A45D 2/00; A45D 6/00; A45D 8/00; A45D 44/00; A45D 2200/00; A41G 5/00; A41G 5/02; A41G 5/0053; A41G 5/004; A41G 5/0046

DESCRIPTION

See application file for complete search history.

FIG. 1 is a top left perspective view of an artificial lash extension in accordance with the claimed design.

(56) **References Cited**

FIG. 2 is a top view thereof.

U.S. PATENT DOCUMENTS

FIG. 3 is a bottom view thereof.

FIG. 4 is a left side view thereof.
FIG. 5 is a right side view thereof.
FIG. 6 is a front view thereof; and,
FIG. 7 is a rear view thereof.

The broken lines consisting of evenly spaced lines in the figures show portions of the artificial lash extension that form no part of the claimed design.
